(57) CLAIM

The ornamental design for an assymmetrical contour shaped vest, as shown and described.

DESCRIPTION

FIG. 1 is a front elevational view of an assymmetrical contour shaped vest

FIG. 2 is a rear elevational view of the assymmetrical contour shaped vest

FIG. 3 is a left side elevational view of the assymmetrical contour shaped vest

FIG. 4 is a right side elevational view of the assymmetrical contour shaped vest

FIG. 5 is a top perspective view of the assymmetrical contour shaped vest

FIG. 6 is a front elevational of a second embodiment of an assymmetrical contour shaped vest;

FIG. 7 is a rear elevational view thereof; and,

FIG. 8 is a top perspective view thereof.

All broken lines are to show environment only and are not part of the claimed design.

The broken line showing on both embodiments of the assymmetrical contour shaped vest is understood to represent stitching.
